SAFETY SPINDLE

Jack D. Nelson 12620 NE. Wasco St.,
Portland, Oreg. 97230

Filed Oct. 17, 1967, Ser. No. 9,073

Term of patent 14 years

Int. Cl. D19—02

U.S. Cl. D74—2

FIG. 1 is a side elevation of a safety spindle in accordance with my new design;

FIG. 2 is a front elevation thereof;

FIG. 3 is a rear elevation thereof;

FIG. 4 is a top plan view thereof;

FIG. 5 is a bottom plan view thereof.

I claim:

The ornamental design for a safety spindle, as shown.
